LONG BEACH, CALIFORNIA

APPARATUS FOR PRODUCING PETROLEUM PRODUCTS

Application filed January 27, 1931. Serial No. 511,593.

This invention relates to apparatus for testing petroleum products, and contemplates a structure embodying mechanical refrigeration as a cooling medium, so that tests can be more accurately and quickly conducted.

In carrying out the invention, I also comprehend an apparatus for the above-mentioned purpose, including refrigerating compartments in which receptacles containing the product to be tested, are adapted to be positioned to be properly cooled for "cold pour" tests, and a cold storage compartment receiving the refrigerating compartments and cooled thereby.

The nature and advantages of the invention will be better understood when the following detailed description is read in connection with the accompanying drawings, the invention residing in the construction, combination and arrangement of parts as claimed.

In the drawings forming part of this application like numerals of reference indicate similar parts in the several views and wherein:

Figure 1 is a rear elevation of the apparatus.

Figure 2 is a sectional view on line 2--2 of Figure 1.

Figure 3 is a top plan view.

Figure 4 is a sectional view on line 4--4 of Figure 3.

The apparatus forming the subject matter of the present invention is in the nature of a cabinet, which of course can be constructed from any suitable material and also vary in size and configuration without departing from the inventive idea. The main body portion of the cabinet is indicated at 10, and provides a cold storage compartment to be hereinafter referred to, the cabinet including a top 11 upon which is arranged a plurality of heat chambers 12. These chambers 12 are arranged side by side and extend longitudinally of the cabinet as clearly illustrated in Figure 3, each heating chamber having air openings 13 and a door 14. Located within each chamber 12 is a heater 15 of any suitable character, each

preferably including a valve 16 actuated by a valve operating rod 17, so that the product to be tested can be distilled at a uniform rate by regulating the flame of the heater. Of course an electrical heater may be also employed without departing from the spirit of the invention.

Located within each heating chamber 12 is a flask 18, preferably an Engler flask which is supported upon an asbestos board 19 having a central opening therein over which the flask is arranged as clearly illustrated in Figure 2. The flask projects through an opening in the top of the heating chamber, and has associated therewith a thermometer 20. The flask 18 is of course adapted to receive a predetermined quantity of the product to be tested, and the particular quantity of said product is measured in a suitable graduated receptacle 21, and subsequently poured therefrom into the flask 18. After the predetermined quantity of the product has been transferred from the graduated receptacle 21 into the flask 18, the said receptacle 21 is then arranged in a position to receive the outlet end of the condenser tube 22. Leading from each flask 18 is a condenser tube 22, arranged at an appropriate angle with relation thereto, and which tube passes through a refrigerating chamber, and has its outlet end positioned within the receptacle 21.

In accordance with the present invention, I contemplate the provision of mechanical refrigeration as a cooling medium, so that the tests can be more accurately and quickly conducted. Consequently, I provide a refrigerating compartment 23 which is copper-lined as indicated at 24, and this refrigerating compartment is arranged at one side of the heating chambers 12, substantially coextensive in length with the cabinet, and common to all of the flasks 18. In other words, the condenser tube 22 from each flask passes through the refrigeration compartment 23 in the manner illustrated in Figure 2, while arranged within the refrigerating compartment are cooling coils 25 positioned above and below the condenser tube 22. The refrigerating compartment 23 is adapted to receive a water bath, which completely surrounds the con-

- denser tubes 22, and the water is maintained in continuous circulation by an agitator 26 which is operated by means of a suitable motor 27'. More than one of these agitators 5 may be employed if so desired. Also rising from the top of the refrigerating compartment 23 are spaced standards 27, one for each thermometer 20, and adjustably supported upon each standard is a magnifying glass 10 to facilitate reading of the thermometer when necessary.
- In practice, a predetermined quantity of the product to be tested is first measured in the receptacle 21, and subsequently poured 15 therefrom into the flasks 18. The refrigerating compartment 23 is then filled with water, and the graduated receptacle arranged upon the cabinet in position to receive the outlet end of the condenser tube 22. It is of course 20 to be understood that there is one of these graduated receptacles 21 used in conjunction with each flask 18 and each tube 22. Heat is then applied at a uniform rate to the flasks 18 and the condensate then starts to fall from 25 the tubes 22 into the receptacle 21. When the first drop falls from the end of the condenser tubes 22 into the adjacent receptacle 21, the reading of the distillation thermometer 20 shall be recorded as the initial boiling point. The heat shall then be so regulated 30 that the distillation will proceed at a uniform rate, and the reading of the distillation thermometer shall be observed and recorded when the level of the distillate reaches 35 each 10 cc, mark on the graduated receptacle 21. The heating shall be continued until the mercury reaches a maximum and starts to fall consistently. The highest temperature observed on the distillation thermometer 40 shall be recorded as the maximum temperature, and usually this point will be reached after the bottom of the flask has become dry. The total volume of the distillate collected in the graduated receptacle shall be recorded 45 as the recovery. The cooled residue shall then be poured from the flask into a small cylinder graduated in 0.1 cc., measured when cool, and the volume recorded as residue. The difference between 100 cc. and the sum 50 of the recovery and the residue shall be calculated and recorded as distillation loss. It has been found that by providing mechanical refrigeration in an apparatus of the class in question, that tests of this character can 55 be more accurately and quickly conducted and that the condenser tubes 22 are always subjected to and maintained at an even temperature.
- As hereinabove stated, the body of the cabinet 60 provides a cold storage compartment indicated generally at 29, and which compartment is provided with doors 30 and drawers 31. Located within the storage compartment 29 is a plurality of refrigerating compart-

ments 31', 32 and 33, the former preferably including a plurality of copper containers 34, each having wound thereabout a heat absorbing coil 35, and each container adapted to individually receive a receptacle containing the product to be tested. The other refrigerating compartments 32 and 33 respectively are preferably in the nature of copper tanks adapted to receive a water bath or other cooling agent, while each tank is also surrounded by heat absorbing coils 36. It will be noted that these refrigerating compartments are arranged within the cold storage compartment 29, and thereby serves to maintain the latter at a proper temperature for the purpose intended. Also, arranged beneath the refrigerating compartments is a drain pan 37 for draining off the moisture brought on by defrosting of the cooling coils as will be readily understood. It is of course to be understood, 55 that sample bottles of oils or other petroleum products are adapted to be inserted in the latter mentioned refrigerating compartment to be cooled for making "cold pour" tests, and these compartments are maintained below zero Fahrenheit temperatures. Manifestly, I have devised an apparatus wherein petroleum products or the like can be quickly, conveniently and accurately tested, and while I have illustrated and described what I consider the preferred embodiment of the invention, I desire to have it understood that I do not limit myself to what is herein illustrated, and that such changes may be resorted to when desired as fall within the scope of what is claimed.

What I claim is:

1. In an apparatus of the character described, a refrigerating compartment adapted to receive a cooling agent, upper and lower spaced groups of cooling coils located immediately adjacent the top and bottom of said compartment, a rotatably mounted agitating element suspended from the top of the compartment and operating in the space between the respective groups of coils, and an inclined condenser tube arranged in the space between said groups of coils and projecting through openings in the opposed side walls of the compartment.

2. In an apparatus of the character described, a refrigerating compartment adapted to receive a cooling agent, upper and lower spaced groups of cooling coils arranged within the compartment, means operating between said groups of coils for agitating the cooling agent within the compartment, an inclined condenser tube arranged in the space between the groups of coils and supported by the opposed side walls of the compartment and projecting beyond said walls, and a flask supported by one end of the tube and communicating therewith.

In testimony whereof I affix my signature.

JAMES G. PHILLIPS.
